ADJUSTABLE LADDER LEG

Walter Scott Young, Peshastin, Wash.

Application July 6, 1946, Serial No. 681,670

3 Claims. (Cl. 228—31)

1

This invention relates generally to an adjustable ladder and more particularly to an adjustable leg and mounting apparatus adapted to cooperate with a two-legged ladder of any type, so that the adjustable three-legged ladder thus formed will be firmly supported and maintained in a laterally virtually erect position on uneven terrain. For example, such a ladder may be used in orchards and the like for picking fruit or for various other purposes where the terrain is not level, as for example, on a hillside. In such case, the third leg may be pivoted in either or both of two directions and so oriented with respect to the terrain as to firmly support and maintain the ladder in a laterally virtually upright position.

Numerous prior art adjustable ladders have attempted to solve this problem. However, such prior art ladders have had numerous disadvantages. One of the major disadvantages of such prior art, adjustable ladder constructions has been the fact that the attachment of the adjustable leg to the ladder was such as to be incapable of properly supporting the ladder when the adjustable leg was moved laterally to any considerable degree with respect to the ladder. In other words, if such an adjustable ladder were used on a hillside and the third leg were moved laterally a considerable distance with respect to the two fixed legs of the ladder, the adjustable, third leg of the ladder would support the ladder so poorly as to make it very likely that the whole ladder would collapse and fall down if any very considerable weight were imposed thereon.

My construction solves this problem in that the adjustable third leg is so mounted with respect to the ladder as to at all times and in all positions firmly and rigidly support the ladder. My invention provides a very simple, rugged construction which is inexpensive to manufacture.

Generally speaking, my invention and construction includes a ladder of any type, generally consisting of a pair of legs and interconnecting rungs, and a stabilizing leg for the ladder. Means are provided whereby the upper end of the stabilizing leg is pivotally connected to the upper portion of the ladder, said pivotal connection including means for pivoting the stabilizing leg toward and away from the plane of the ladder and means for pivoting the stabilizing leg about an axis passing through the plane of the ladder. The leg itself may be provided with an adjustable extension, if desired. Selectively operable means carried by the stabilizing leg are provided for locking the leg in any desired pivotal position. By this construction the third or stabilizing leg may be positioned at any desired angle and thereby firmly sustain the ladder itself. By employing but a single stabilizing leg,

2

such leg may be readily inserted through branches of trees when the ladder is used for picking fruit.

It is an object of this invention to provide an adjustable leg and mounting apparatus adapted to cooperate with a two-legged ladder for firmly supporting and maintaining the ladder in a laterally virtually erect position regardless of the terrain.

5 10 It is a further object of this invention to provide an adjustable leg and mounting apparatus adapted to cooperate with a two-legged ladder of relatively simple, cheap, rugged construction and having great structural strength regardless 15 of the position of the adjustable leg with respect to the ladder.

20 Other and allied objects will be apparent to those skilled in the art upon a careful examination and perusal of the specification, drawings, and appended claims.

25 Referring to the drawings:

Fig. 1 is a front perspective view of a ladder with the adjustable leg and mounting apparatus of my invention mounted thereon.

25 30 Fig. 2 is a rear elevation of the ladder shown in Fig. 1.

Fig. 3 is an enlarged fragmentary sectional view of the ladder taken along the plane III—III of Fig. 2 showing details of the apparatus of 30 my invention.

35 Fig. 4 is an enlarged fragmentary elevation of the ladder taken along the plane IV—IV of Fig. 3 showing the details of the apparatus of my invention.

40 45 More specifically, a ladder indicated generally at 1 is provided with two, parallel, opposed legs 2 and 3 between which are positioned a plurality of spaced, parallel rungs or steps 4. Attachment members 5 and 6, which preferably may be sheet metal or the like, are riveted, bolted, or otherwise suitably attached to the tops of the parallel legs 2 and 3 adjacent and beneath the top 36 of the ladder 1. The attachment members 5 and 6 extend rearwardly from the ladder and a longitudinal channel member 7, which may be made of

50 metal or any other suitable material, and which is provided with downwardly bent lips 8 and 9 at the outer ends thereof is rotatably mounted between the outwardly extending portions of the attachment members 5 and 6 by bolts 10 and 11, and cooperating nuts, rivets, studs, or any other suitable means for rotation or pivotal movement about an axis lying in a plane parallel to the plane of the ladder.

55 60 Fixedly attached to the downwardly bent lips 8 and 9 at opposite ends of the channel 7 are the ends of a semicircular guide member indicated generally at 12, which may be made of metal or any other suitable material. The semicircular guide member 12 includes two flanged

portions virtually perpendicular to each other. One flanged portion 13 extends radially outwardly; the other flanged portion 14 is virtually perpendicular to the flange 13 and extends generally toward the front of the ladder. The flange 14 is provided with spaced apertures 15.

An adjustable leg 16 provided with a suitable attachment member 17, which may be made of metal or any other suitable material, is pivotally attached to the channel member 7 within the outwardly extending edges 18 and 19 and preferably at the center thereof indicated at 20 by means of a bolt and a nut, rivet, stud, or any other suitable means.

Also mounted upon the adjustable leg 16 is a cooperating guide means indicated generally at 21 comprising two, spaced, bent members 22 and 23, which may be made of metal or any other suitable material, adapted to be positioned on each side of both flanges 13 and flanges 14 of the semicircular guide member 12. The two, spaced, parallel members 22 and 23 are fixed to the adjustable leg 16 by rivets 24 or any other suitable means.

The portions of the two, spaced, parallel members 22 and 23 which are positioned on each side of the radially, outwardly extending flange 14 of the semicircular guide member 12 are adapted to prevent relative movement between the adjustable leg 16 and the semicircular guide member 12 in a plane virtually transverse to the plane of said semicircular guide member 12. The portions of the two, spaced members 22 and 23 which are positioned on each side of the other flange 14 of the semicircular guide member 12 are provided with aligned apertures 25 which are spaced on opposite sides of the flange 14 which is provided with apertures 15 therein.

A spring-biased locking means indicated generally at 26 is also mounted upon the adjustable leg 16. The spring-biased locking means 26 includes a plunger 27, which may be made of metal or any other suitable material, provided with a shoulder 28. A coil compression spring 29 is adapted to be positioned between the shoulder 28 and an outwardly extending lip 30 which is fixed to the leg 16 and in the example shown is attached to the cooperating guide means 21. A wire, cable or the like 31 is fixed to the lower end of the plunger and is connected to a suitable handle 32 for actuating the plunger 27. The coil spring 29 which is compressed between the shoulder 28 and lip 30 normally urges the plunger 27 in an upward direction and the plunger 27 is adapted to pass through the aligned apertures 25 in the cooperating guide means 21 and any one of the apertures 15 in the flange 14 of the semicircular guide member 12 for fixing the position of the adjustable leg 16 with respect to the semicircular guide member 12.

The assembly comprising the semicircular guide member 12 and the channel 7, which is fixed with respect to the semicircular guide member 12, and the adjustable leg 16, which is transversely fixed with respect to the semicircular guide member 12 by means of the cooperating guide means 21, is pivotally movable as a unit toward and away from the plane of the ladder about pivot points indicated generally at 33 and 34, or, in other words, about an axis virtually parallel to the longitudinal axes of the steps of the ladder or the top of the ladder. The adjustable leg 16 is pivotally movable in a transverse plane about the pivot point 20 (about an axis passing through the plane of the ladder) whenever the handle 32 for actu-

ating the locking means 26 is manually actuated so as to move the plunger 27 downwardly and disengage the plunger 27 from the apertures 15 in the semicircular guide member 12. When the desired lateral adjustment or position is reached, the handle 32 is released, thus allowing the coil spring 29 to force the plunger 27 through the aligned apertures 25 in the cooperating guide means 21 and the apertures 15 in the flange 14 of the semicircular guide member 12, thus preventing any further movement of the adjustable leg 16 about the pivot point 20.

Thus the adjustable leg 16 may be adjusted about two axes perpendicular with respect to each other. It can readily be seen that since the point of attachment of the channel member 7 and the semicircular guide member 12 which is fixed thereto is immediately adjacent the legs 3 and 4 of the ladder, this construction has great structural strength.

The operation of the ladder, including the adjustable leg and mounting of my invention, may be described as follows:

If it is desired to position the ladder in a laterally virtually upright or erect position with the ladder firmly supported upon terrain or ground which is inclined, the two legs of the ladder are positioned in the desired position and the adjustable third leg is pivoted about points 34 and 35 and until the adjustable leg 16 is in the desired position in that plane. Then the handle 32 is actuated for releasing the locking means 26 and the adjustable leg 16 is pivoted about the pivot point 20 in the plane of the semicircular guide member 12 until the desired position of the adjustable leg 16 is reached in that plane, the relative movement of the adjustable leg in the two planes being such as to position the ladder in the desired position, regardless of the terrain or regardless of obstacles or obstructions which may be positioned immediately behind or adjacent to the ladder. This is extremely desirable in such work as fruit picking, pruning, or the like.

It can be seen that the construction of my invention is structurally strong and well adapted to firmly support the ladder, no matter what position the adjustable leg may be in with respect to the ladder, because the mode of attachment to the ladder imparts great torsional rigidity and strength to the third leg about its lateral pivotal mounting point when locked with respect to the semicircular guide member.

There are numerous possible modifications of this idea. For example, the channel member 7 need not be a channel member at all but may be any transverse member pivotally mounted about an axis virtually parallel to the longitudinal centerline of the steps of the ladder or the top of the ladder taken between the legs thereof. The pivotal attachment of said transverse member 1 to the opposed legs of the ladder may be varied in any suitable manner. Said transverse member may be attached to the top or steps of the ladder adjacent the legs thereof. The attachment members 5 and 6 are only one of many possible ways of pivotally attaching the transverse member adjacent the top of the ladder. The adjustable leg 16 may be provided with various types of attachments for pivotally attaching the leg 16 to the transverse member 7 or it may be pivotally attached to the transverse member 7 directly in any suitable manner. The semicircular guide member 12 which is fixed to the transverse member 7 may be of any desired cross section. For ex-

ample, it may have angularly related flanges instead of virtually perpendicular flanges, or it may be of an entirely different cross section. It may be welded or otherwise suitably fixed to the ends of the transverse member 7 adjacent the ends thereof. The cooperating guide means 21 may be any suitable means adapted to engage the semicircular guide member 12 and restrict movement to the transverse plane thereof. The cooperating guide means 21 may be dispensed with entirely, if so desired, and reliance placed entirely upon the locking means 26 for preventing movement of the adjustable leg 16 with respect to the semicircular guide member 12 in either direction. The locking means 26 may be normally spring-biased closed, as shown, or it may normally be open and manually, selectively closable. The locking means may take an entirely different form from that shown in the illustrations herein. Any suitable locking means adapted to selectively cooperate with and engage the semicircular guide member 12 so as to prevent movement in the plane of said semicircular guide member 12 may be used.

I claim:

1. An adjustable leg and mounting apparatus adapted to cooperate with a two-legged ladder comprising: a longitudinal channel member pivotally mounted with respect to the ladder adjacent and virtually parallel to the top and between and virtually perpendicular to the opposed legs thereof, said longitudinal channel being provided with a radially, outwardly extending, semicircular guide member having two virtually perpendicular flanges, one of which extends radially outwardly and the other of which is provided with spaced apertures therein; an adjustable leg pivotally attached to the longitudinal channel member at the center thereof and within the outwardly extending edges of the channel so as to pivot in a plane virtually parallel to or containing said channel member; cooperating guide means mounted upon the adjustable leg comprising two, bent, spaced members adapted to be positioned on opposite sides of both perpendicular flanges of the semicircular guide member, the portion of the cooperating guide means positioned on each side of the radially, outwardly extending flange of the semicircular guide member being adapted to prevent relative movement between the adjustable leg of the semicircular guide member transverse to the plane of the semicircular guide member, the portion of the cooperating guide means positioned on each side of the other flange of the semicircular guide member being provided with aliened apertures; and spring biased, normally locked but manually selectively releasable, locking means mounted upon the adjustable leg and adapted to cooperate with aligned apertures in the semicircular guide member and cooperating guide means for controlling pivotal movement of the adjustable leg about its pivotal attachment to the channel member.

2. An adjustable leg and mounting apparatus adapted to cooperate with a two-legged ladder comprising: a longitudinal channel member pivotally mounted with respect to the ladder adjacent the top and between the legs thereof so as to pivot about an axis virtually parallel to the longitudinal centerlines of the steps of the ladder and between the legs thereof, said longitudinal channel being provided with an outwardly extending, semicircular guide member having two angularly related flanges, one of which extends

outwardly and the other of which is provided with spaced apertures therein; an adjustable leg pivotally attached to the longitudinal channel member adjacent the center thereof so as to pivot in a plane virtually parallel to or containing said axis; cooperating guide means mounted upon the adjustable leg comprising two, bent, spaced members adapted to be positioned on opposite sides of both angularly related flanges of the semicircular guide member, the portion of the cooperating guide means positioned on each side of the outwardly extending flange of the semicircular guide member being adapted to prevent relative movement between the adjustable leg of the semicircular guide member transverse to the plane of the semicircular guide member, the portion of the cooperating guide means positioned on each side of the other flange of the semicircular guide member being provided with aligned apertures; and spring biased, normally locked but manually selectively releasable, locking means mounted upon the adjustable leg and adapted to cooperate with aligned apertures in the semicircular guide member and the cooperating guide means for controlling pivotal movement of the adjustable leg about its pivotal attachment to the channel member.

3. An adjustable leg and mounting apparatus adapted to cooperate with a two-legged ladder comprising: a longitudinal channel member pivotally mounted with respect to the ladder adjacent the top and between opposed legs thereof so as to pivot about an axis virtually in a plane parallel to or the same as the plane of the ladder and virtually parallel to the steps of the ladder, said longitudinal channel being provided with a radially, outwardly extending semicircular guide member having two virtually perpendicular flanges, one of which extends radially outwardly and the other of which is provided with spaced apertures therein; and adjustable leg pivotally attached to the longitudinal channel member at the center thereof and within the outwardly extending edges of the channel so as to pivot in a plane virtually parallel to or containing said axis; cooperating guide means mounted upon the adjustable leg adapted to cooperate with the outwardly extending flange of the semicircular guide member for preventing relative movement therebetween transverse to the plane of the semicircular guide member; and spring biased, normally locked but manually selectively releasable, locking means mounted upon the adjustable leg and adapted to cooperate with the semicircular guide member for controlling pivotal movement of the adjustable leg about its pivotal attachment to the channel member.
